START-STOP REGENERATIVE REPEATER

Filed Feb. 16, 1934

UNITED STATES PATENT OFFICE

2,104,273

START-STOP REGENERATIVE REPEATER

Louis M. Potts, Evanston, Ill., assignor to Teletype Corporation, Chicago, Ill., a corporation of Delaware

Application February 16, 1934, Serial No. 711,479

30 Claims. (Cl. 178—70)

This invention pertains to telegraphy and more particularly to the automatic transmission of telegraphic signal codes from one line section to another.

5 In telegraph systems using comparatively long signal impulses, relay repeaters which renew the current value in each impulse but which may modify the length of the impulses slightly have been found satisfactory for some telegraphic purposes, but in systems where transmission is effected at high speeds, it becomes necessary to preserve the relative lengths of signal impulses as well as to renew the current strength thereof. Accordingly, an object of this invention is to provide 15 a repeater for start-stop systems of automatic telegraphy in which received signal impulses are reproduced and retransmitted in renewed strength and in faithful reproduction of their relative time value, thereby producing a complete regeneration of the signal impulses and signal conditions as originally created and transmitted.

Further features are to repeat and regenerate the start and stop control impulses as well as 25 the intelligence impulses and to provide a start-stop regenerative repeater in which relative lengths of retransmitted impulses are determined locally by mechanical means, but in which an electrical characteristic of each repeated impulse is determined by a received signal impulse to which the retransmitted impulse corresponds.

These and other objects are attained by utilizing the principles of a speed regulated motor shaft and start-stop control for synchronizing the receiving and retransmitting functions taken in connection with cam controlled retransmitting contacts which, by start-stop principles, are kept in synchronism with the incoming signal impulses.

40 The system of this invention comprises a regenerative repeater which is associated with a circuit arrangement to repeat in but one direction, but it is to be understood that the apparatus is such that it may be used in circuit systems in which repeating in both directions upon a single telegraphic line system may be conducted. Apparatus achieving such an object is disclosed in copending application Serial No. 755,253, filed Nov. 30, 1934.

45 The apparatus of the present invention comprises a start-stop cam or set of cams with a driving motor and with a clutch which permits the cams to be normally stopped but in condition to be started in response to a received signal. 50 In response to a received starting impulse, the

cams start and continue in motion for a complete code cycle of operation, then come to rest in readiness for the next cycle. Retransmitting contact points are arranged to be dually controlled, first by the cams to determine the length of every signal impulse and second, by means responsive to received signal impulses to determine the electrical characteristic of each retransmitted impulse according to the received impulse which it represents, the start impulse and stop impulse being repeated as well as the intelligence impulses of each code group of impulses.

55 A better understanding of the invention may be had from the following description, taken in connection with the accompanying drawing, 15 wherein

Fig. 1 shows a telegraphic system comprising two line circuits associated in signal repeating relation by a repeater of preferred type according to the present invention; 20

Fig. 2 shows an alternative type of repeater; Fig. 3 shows a detail of the repeater of Fig. 2;

Fig. 4 shows a modification of the repeater of Figs. 2 and 3;

Fig. 5 shows an alternative type of repeater; 25

Fig. 6 shows a detail of the repeater of Fig. 5;

Fig. 7 shows a modification of the repeater of Fig. 5; and

Fig. 8 shows a starting latch.

Referring to Fig. 1, a controlling line circuit 30 includes battery 1, receiving magnet 2, line wire 3, remote transmitter 4, and ground 5, and a controlled line circuit includes battery 6, resistor 7, contact 8, contact 9, line wire 10, receiver magnet 11, and ground 12. Magnet 2 has an 35 armature 15 pivoted at 16 with retractile spring 17 having selective abutments 18, 19, and with a striker 20 for controlling a starting mechanism, not shown, for starting a cam sleeve 21. The starting mechanism may be of the type shown 40 in Patent No. 1,783,382, issued to H. L. Krum and comprising in part a friction clutch and a clutch releasing latch, although any other type of clutch and latch suitable for printing telegraph equipment may be used. In Fig. 8, upon release of 45 armature 15, striker 20 pushes pin 115, which rotates levers 116 and 117 to release a starting latch 118 whose tooth 119 releases arm 101 fixed upon friction-urged cam sleeve 21. Cam sleeve 21 is associated through a friction clutch with 50 a constantly operating power shaft 26, and carries a multiple cam 27 having lobes which consecutively engage a cam follower 28 pivoted at 29 with retractile spring 30. Follower 28 has also a socket arm 33 which surrounds a disc like head 55

34 of T-member 35 which has abutment extensions 36, 37 and a slotted arm 38. Within the slotted arm 38 is contained an operating pin 42 fixed upon lever 43, pivoted at 44 and having 5 jockey 45. Striker 46 secured to member 35 engages contact 47 to move it into engagement with contact 9 normally in engagement with contact 8.

In operation, the structure shown in Fig. 1 normally has magnet 2 energized, its controlling 10 circuit being normally closed at transmitter 4 as shown, with its armature in operated position as shown. Signal impulses are transmitted over line 3 in code groups of seven impulses per group, each group beginning with a spacing or open 15 impulse and terminating with a marking or current impulse. The first signal, spacing, of a received code of signals will deenergize magnet 2 and release armature 15, thus causing striker 20 to start cam sleeve 21 and also will position abutment 19 in apposition with abutment 36. Immediately cam 27 starts revolving and lobe 50 operates follower 28 to operate T-member 35, which causes abutment 36 to engage abutment 19 and which rotates member 35 upon abutment 25 19 as a fulcrum, so that slotted arm 38 acts through pin 42 to rotate lever 43 which is locked in its operated position by jockey 45 and which, in its operated position, operates contact 47 to engage contact 9 and to lift contact 9 away 30 from contact 8, thus opening controlled line circuit 10 and repeating a spacing signal of no-current in controlled line circuit 10 in response to a similar spacing signal in controlling line circuit 3.

35 The above described action comprises repeating the starting signal impulse of a code, following which five intelligence impulses and a stop impulse are repeated by cam lobes 51 to 56 inclusive in cooperation with armature 15 controlled 40 by magnet 2. As each lobe 50 to 55 inclusive operates follower 28, the member 35 is moved to engage either abutment 19 or abutment 18 and therefore operates lever 43 to or from its marking position as shown accordingly as a received 45 signal impulse is marking or spacing in nature. A signal in controlling line circuit 3, whether marking or spacing, determines the condition of magnet 2, whether energized or deenergized, which determines the position of armature 15, 50 whether attracted for marking or released for spacing, which determines the effectively positioned one of abutments 18, 19, whether 18 for marking or 19 for spacing, after which the retransmitted impulse will be determined in feature of its duration and in feature of its elapsed time relation to the starting impulse wholly by the mechanical action of the cam 27 which is driven by a local motor running at a constant speed, and the retransmitted impulses thus are 55 given relative lengths determined by local mechanical means at the repeating apparatus regardless of the relative length of the marking and spacing signals as received by magnet 2 over line circuit 3.

60 65 In an apparatus for polar working, magnet 2 may be of polar type and contact 47 may be connected through a resistor as 7 to a battery as 6, but of reversed polarity, the contact 9 then operating with contacts 8 and 47 to produce polar 70 reversals of current in line 10 as the contacts are operated by lever 43.

An alternative mechanical form of the invention is shown in Figs. 2 and 3. For a more comprehensive explanation of the mechanical details 75 of this structure, reference may be had to Pat-

ent No. 1,821,110 issued to S. Morton et al. September 1, 1931, and to Figs. 1 and 3 thereof particularly. Cam barrel 51' symbolizes a complete printer such as disclosed in the patent to Morton et al. and when taken with the addition of signal lever 52' and multiple lobe cams 53' and 54' for marking and spacing signals respectively, Fig. 3 discloses a combination printer and start-stop regenerative repeater. Cam barrel 51' has stop arm 55' which engages a fixed stop dog 56' and 10 a signal lever 52', corresponding to signal lever 43' in Fig. 1, has jockey 57 corresponding to jockey 45 in Fig. 1, and has striker 58 corresponding to striker 46 in Fig. 1 whereby contacts 47', 9', and 8' are operated as in Fig. 1.

15 In the Morton et al. printer, the cam barrel 51' has six pairs of cams 50' which control six selector levers in accordance with six received intelligence impulses, operating the selector levers sequentially to register each impulse as the 20 intelligence impulses are received, after which a transfer action occurs which transfers the six registrations simultaneously to the selector and printing mechanism of the printer. Added to the Morton et al. mechanism is the special signal lever 52' for repeating the received impulses. The special lever 52' is coaxial with the six regular selector levers of the printer, and operates to marking and to spacing positions in a manner similar to the operation of the printer selector levers but operates for every impulse of the 25 entire signal including start and stop impulses. With every movement of the special signal lever 52' it changes the contactual relations of the contacts 8', 9', and 47' and causes them to transmit to the controlled line section 10' a signal impulse corresponding to the instant signal impulse in the controlling line section. The special signal lever 52' is not associated with the transfer mechanism which cooperates with the six signal levers of the printer's printing mechanism, so that the transfer action and subsequent actions of the printer are not effective upon the retransmission mechanism.

30 35 In operation, as a repeater, the structure shown in Figs. 2 and 3 normally has cam barrel 51' in position toward the left as shown, it being held in that position under control of an energized line magnet corresponding to magnet 2 in line circuit 3 of Fig. 1. Signal impulses are 40 transmitted over line 3 in code groups of seven impulses per group, each group beginning with a spacing or open impulse and terminating with a marking or current impulse. The first signal, spacing, of a received code of signals will release cam barrel 51', as will be understood from the Morton et al. patent. The cam barrel will move 45 toward the right to clear stop dog 56', will move marking cam 53' away from upper cam follower 59 of lever 52', move spacing cam 54' into position to engage lower cam follower 60 of lever 52', and will begin a revolution at regulated speed. Immediately thereafter, a lobe of cam 54' engages follower 60 and moves lever 52' into its 50 alternative position and operates striker 58 and contacts 47' and 9', thereby disengaging contact 9 from contact 8' and opening controlled line circuit 10' and repeating a spacing signal impulse of no-current in controlled line circuit 10' in response to a similar spacing signal impulse in 55 controlling line circuit 3. The above described action comprises repeating a starting signal impulse of a code, following which five intelligence impulses and a stop impulse are repeated by cam barrel 51' in cooperation with contacts 47', 9', and 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 and 8'. As each impulse, whether marking or spacing, operates cam barrel 51' to left or to right accordingly as the controlling impulse is marking or spacing, lever 52' is brought under control of cam 53' or 54' accordingly as the impulse is marking or spacing, and a lobe of the then effective cam 53' or 54' determines the position of lever 52', which in turn determines the operation of contacts 47', 9', and 8'. The time duration and electrical nature of a retransmitted impulse, and its time relation to its starting impulse, will be determined wholly by the mechanical action of cam barrel 51' which is driven by a local motor running at a constant speed, while the electrical nature of each retransmitted impulse will be determined by the left or right position of cam barrel 51', as determined in turn by the marking or spacing nature of a signaling impulse of the instant electrical signal in the controlling line.

In Fig. 4 is shown a development of cams 53' and 54' shown in normal form in Figs. 2 and 3. A modification is shown in cam lobes 53A and 54A in that the two said lobes are extended in axial dimension in such manner that lobe 54A always engages cam follower 60 to operate signal lever 52' whether cam barrel 59' is positioned to right or to left by a received signal, and lobe 53A always engages cam follower 59 to operate signal lever 52' whether cam barrel 59' is positioned to right or to left. Thus, start and stop signals of proper timing and of proper electrical characteristic are sent to line 10' independently of control by any received signal, and only the intelligence impulses are repeated under direct control of received signals.

A further mechanical type of the invention is shown in Fig. 5 with a detail in Fig. 6. For a more comprehensive explanation of this structure, reference may be had to Patent No. 1,370,669, issued to L. M. Potts, March 8, 1921, and to Fig. 18 thereof particularly. In the Potts patent is disclosed a method of operating a receiving device in which a detector lever is supported loosely at both ends and is spring tensioned near one end and between the supports. A cam applies power to a median point of the lever and the non-tensioned end operates if the lever is unrestrained, but should the non-tensioned end be restrained as a result of a line signal, then the tensioned end of the lever will respond to the cam. Thus a spacing signal impulse of no-current in the line circuit will restrain the non-tensioned end of the detector lever and cause the cam to operate the tensioned end of the detector lever to operate in turn a signal lever to register a space signal, while a marking signal impulse of current in the line circuit will not restrain the detector lever and will permit the cam to operate the non-tensioned end of the detector lever to operate in turn a signal lever to register or indicate a marking signal impulse.

In the structure of Figs. 5 and 6, illustrated in two sectional views in exploded arrangement of upper and lower views a continuously operating motor power shaft 61 is connected through a friction clutch with a single cam sleeve 62 which sleeve is integral with one cam 63 in the upper view and with five pairs of mated cams 64 and 65 in the lower view, the eleven cams cooperating severally with eleven cam follower levers comprising one of the levers 79 in the upper view, five of the levers 95, and five of the levers 103 in the lower view. Cam 63 cooperates with a cam follower lever 68 which is held yieldingly by

spring 69 against stop 70 and pivotal stop 71 with cam follower 72 projecting into the path of lobes 73 and 74 of cam 63. Striker 77 on cam follower lever 68 may engage lug 78 on signal lever 79 pivoted at 80 to rotate lever 79 clockwise, and striker 81 on cam follower lever 68 may engage lug 82 on signal lever 79 to rotate lever 79 counterclockwise. Signal lever 79 is normally restrained by jockey 83 and operates contacts 84. Magnet 85 shown in the lower view has an armature 86 which is pivoted at 87 and which has retractile spring 88 and which has also an operating edge 90 shown in both upper and lower views which normally is out of the path of ends 91 of lever 68 in the upper view and 95 in the lower view, and normally is held in that position by energization of magnet 85 corresponding to magnet 2 of Fig. 1. Armature 86 has also a cam-starting striker 92 corresponding to striker 20 in Fig. 1.

Cam 64 cooperates with a cam follower lever 95 which is held yieldingly by spring 96 against stop 70 and pivotal stop 71 with cam follower 97 projecting into the path of cam 64. Striker 98 on cam follower lever 95 may engage lug 99 on signal lever 102, pivoted at 80, to rotate lever 102 clockwise.

Cam 65 cooperates with a cam follower lever 103 which is held yieldingly by a spring similar to 96 against stops 70 and 71 with a cam follower similar to 97 projecting into the path of cam 65. Striker 104 on cam follower lever 103 may engage lug 105 on signal lever 102 to rotate lever 102 counterclockwise. Lever 103 is largely obscured by lever 95 in Fig. 5. The contour of lever 103 is similar to the contour of lever 95 except that lever 103 terminates at 106 and has neither operating end 91 nor striker 98 for rotating lever 102 clockwise, but has instead striker 104 for rotating lever 102 counterclockwise. Both levers 95 and 103 are guided by comb 107, Fig. 6, in which lever 95 moves freely in a deep notch and in which lever 103 is restrained by a shallow notch against movement in response to cam 65, Fig. 5.

Signal lever 102 operates contacts 108, there being five pairs of cams 64, 65, five pairs of cam follower levers 95, 103, five signal levers 102, and five pairs of contacts 108 all corresponding to five intelligence signal impulses in a received code of impulses, additional similar equipment being provided when longer codes are served. Successive pairs of cams 64, 65 are spaced at successive angles upon cam sleeve 62. A controlled line circuit extends from ground 111 through battery 112 and resistor 113, then through all contacts 108 and 84 in parallel to line wire 114.

In operation generally, in the structure of Fig. 5, cam lobe 73 operates lever 79 to open contacts 84 to repeat a starting signal of spacing or open electrical nature, followed by successive operation of five levers 102 to operate five pairs of contacts 108 in successive intervals of open or closed electrical conditions as determined by the received controlling signal impulses, followed by the operation of lever 79 by cam 74 to close contacts 84 in response to a stop signal impulse of closed circuit electrical nature.

In operation specifically, when a starting signal impulse of open circuit condition deenergizes magnet 85, armature 86 is operated by spring 88 and striker 92 operates a clutch (not shown) to start cam sleeve 62 and its cams 63, 64, and 65. Armature 86 being deenergized, operating edge 75

90 now is positioned in the path of all ends 91 and cam lobe 73 engages follower 72 and operates lever 68 which being restrained at end 91 by edge 99 rotates upon edge 90 as a fulcrum and causes spring 69 to yield, thus causing striker 81 to operate lever 79 which rotates upon its pivot 80 and operates contacts 84 to open retransmission circuit 114. This constitutes the repeating of the starting impulse of a code now being received. At a time instant thereafter, during a median part of the first intelligence impulse signal, signal receiving magnet 85 will be energized or deenergized according to the marking or spacing nature of the first intelligence signal impulse, armature 86 will be attracted or unattracted according to the marking or spacing nature of the impulse, edge 90 will be out of or in the path of end 91 of the first lever 95 according to the marking or spacing nature of the impulse, first 20 cam 64 will engage first cam follower 97 and will operate end 91 on 71 as a fulcrum or will operate end 120 on 90 as a fulcrum according to the marking or spacing nature of the impulse, as a result of which the first lever 102 will be moved 25 clockwise by engagement of striker 98 with lug 99 or will not be moved according to the marking or spacing nature of the impulse, by which the first pair of contacts 108 will be closed or will remain open according to the marking or spacing 30 nature of the first intelligence signal impulse, thus repeating in the controlled circuit 114 the instant marking or spacing signal impulse of a controlling circuit in which magnet 85 is included. Thereafter at a similar instant of the 35 second intelligence signal impulse, cam 65 invariably will engage cam follower (not shown) of lever 103 and invariably will operate striker 104 to operate lever 102 counterclockwise to permit the first contacts 108 to open, this restoration of 40 the first pair of contacts occurring simultaneously with the operation of the second lever 102 by the cam 64 of the second pair of cams, thus terminating the first retransmitted intelligence impulse and initiating the retransmission of the 45 second intelligence signal impulse. In like manner the third, fourth, and fifth intelligence signal impulses are repeated, and as the fifth cam 65 terminates the fifth retransmitted intelligence signal impulse, cam lobe 74 operates lever 50 68 for retransmission of the stop signal impulse which always is of marking nature with magnet 85 energized, with armature 86 attracted, and with edge 90 out of the path of end 91 of lever 68 and striker 77 invariably is operated to engage 55 lug 79 to rotate lever 79 to cause contacts 84 to close, thus retransmitting the stop signal. In the transmission of the code as described, each instant of beginning and ending of every retransmitted signal impulse has been timed by local 60 mechanism driven by a local speed regulated motor, and every impulse including starting and stopping impulses have been governed in electrical nature by an electrical signal instantly existing in a controlling circuit.

65 By positioning each cam 65 in an angular position between its preceding cam 64 and its following cam 64, there will be attained the effect of opening the controlled circuit 114 after each and every intelligence impulse and therefore 70 between consecutive impulses when such form of signal transmission is desired.

A modification of the structure of Fig. 5 is shown in Fig. 7 wherein all contacts 108 and all levers 95, 103, 102, are omitted and all cams 65 75 are omitted, the cams 64 being transferred to

the cam 63 and appearing thereon as lobes 121 to 125 inclusive. The operation of the structure of Fig. 7 is identical with the operation of the structure of Fig. 5 in the manner of start and stop impulses and at each intelligence impulse instant, edge 91 will be positioned according to the nature of the received signal impulse, lever 68 will be operated at one end or the other according to the nature of the received signal impulse, and contacts 84 will be closed or will be permitted to open according to the nature of the received intelligence impulse. In each retransmitting operation, the time is controlled by local motor and cam and the nature of the retransmitted impulse is controlled by the instant received signal impulses in the controlling line circuit.

Throughout the several species and modifications in which the present invention has been illustrated for purpose of complete description, the following generic features will be noted. The 20 mechanical design for cam starting, cam driving, and cam controlling has been taken in conformity to designs of selectors for receiving printers, and in each species a design shown is suitable for attachment to a receiving printer to form a combined receiver-printer-repeater. In each species the retransmission is effected by power driven contacts, the control of the received signal being exercised in the function of determining whether or not the motor shall shift the contacts, thereby 25 attaining a condition for utilizing contacts of considerable mechanical strength, of firm contact pressure, and of great reliability. Designs are shown in which but a single contact tongue is used, thereby achieving great simplicity.

Reference is made to application Serial No. 712,461 to Walter J. Zenner, filed February 23, 1934, which discloses one form of a start-stop regenerative repeater.

What is claimed is:

1. In a telegraphic repeating device, a contact member for retransmitting a received signal, an armature controlled by a received signal, and a timing cam started into operation under the control of said armature for timing retransmitted signals and cooperating with said armature for operating said contact member in accordance with the instant position of said armature to control the character of the retransmitted signals.

2. In a telegraphic repeating device, a contact member for retransmitting received signals, an element controlled by successive received signals, a locking member restraining said contact member in its set position, and a timing cam cooperating with said element and operating said contact member repeatedly to control timing of successive retransmitted signals as determined by said element.

3. In a telegraphic repeating device for equal length signal intervals, a contact member for retransmitting received signals, an armature controlled by successive received signals, a locking member restraining said contact member, a multiple lobed timing cam, a latch operable by said armature to start said timing cam at the beginning of each signal interval, and a cam follower for said timing cam releasing said contact member successively during each cycle of rotation of said cam to control timing of successive retransmitted signals during each signal interval.

4. In a telegraph device, a single contact member for retransmitting a received signal, an element controlled by a received signal, a cam controlled by said element, and means dually controlled by said cam and said element and oper-

ating said contact member at a predetermined instant to retransmit an instantly received signal.

5. In a telegraphic repeating device, a contact member for retransmitting received signals, an armature controlled by successive received signals, a start-stop multiple lobed cam, and means dually controlled by said cam and by said armature and operating said contact member repeatedly at 10 predetermined instants to retransmit directly a group of received signal impulses during a single cycle of said cam.

6. In a telegraphic repeating device, a contact member for retransmitting received signals, an armature controlled by successive received signals, a multiple lobed cam, means dually controlled by said cam and by said armature and operating said contact member at predetermined 15 instants to retransmit a plurality of received signal impulses during each cycle of said cam, and a latch operable by said armature in response to a received timing signal to start said cam.

7. In a telegraphic repeating device, an armature controlled by a received signal, a contact member, and cam operated mechanism started under control of said armature and cooperating with said armature for operating said contact member to retransmit said received signal under instant control of said armature.

30 8. In a telegraphic repeating device, an armature controlled by successive received signals, a single contact member, cam operated mechanism started by said armature and adapted to operate said contact mechanism at successive instants 35 of beginning of a plurality of signal time intervals, and means associated with said armature for controlling said cam operated mechanism in accordance with the electrical nature of an instantaneously received signal.

40 9. In a telegraph repeater, a signal timing device comprising a multiple lobed timing cam, means for starting said cam upon receipt of a received timing signal, means for retransmitting signals under control of said cam at each instant of beginning of time intervals of a plurality 45 of signals, and means controlled by successively received signals at the instant of beginning of retransmission of each received signal and controlling said retransmitting means to determine the electrical nature of each retransmitted signal.

50 10. In a regenerative repeater, a retransmitting contact, a motor driven cam to operate said retransmitting contact to retransmit start and stop signals invariably at fixed time intervals after receipt of a starting signal, and means under control of other signals to render said cam effective to operate said retransmitting contact variably at other fixed time intervals and in accordance with received signals.

55 11. In a regenerative repeater, a transmitting contact, a motor driven cam barrel to operate said contact invariably to transmit start and stop signals at fixed time intervals after receipt 60 of a starting signal and shifted axially in response to received signals, and means associated with said cam barrel and with said transmitting contact to render said cam barrel effective in its shifted positions to operate said transmitting contact variably at other fixed time intervals and in accordance with received signals.

65 12. In a telegraph system, means to transmit code signals, a magnet armature operated according to said signals, a rotary member, means 70 to control the phase of the rotary member direct-

ly by said armature, and a second means to retransmit said code signals controlled jointly by the rotary member and the position of said armature at the instant of beginning of repeating each signal impulse. 5

13. In a regenerative repeater, a magnet controlled by received signals, an armature for said magnet, a motor driven rotatable cam controlled to start into rotation by said magnet, and a retransmitting contact whose position in successive intervals of time is determined by said armature and the time of beginning and end of the intervals is determined by said rotatable cam. 10

14. In a regenerative repeater, a magnet controlled by received signals, an armature for said 15 magnet, a motor driven rotatable cam controlled to start into rotation by said magnet, and a retransmitting contact whose position in successive retransmitting intervals of time is determined by said armature and the length of the 20 retransmitting intervals is determined by said rotatable cam.

15. In a telegraph system, means controlled by a received line signal, a contact element adapted to transmit regenerated impulses, a start-stop 25 rotary member, means to lock the contact element in either marking or spacing position, and means to change the contact element from one position to the other under the dual control of said rotary member and said first mentioned 30 means within intervals of control which are small in comparison with the length of the said regenerated impulses.

16. Telegraphic apparatus including a member having motion in lineal and rotary directions, 35 power driven means to move said member, yielding means opposing the motion of said member in rotary direction, selectively operated means controlled by received signals to oppose the motion of said member in lineal direction to cause it to 40 move in rotary direction against said yielding means, and a retransmitting contact operable by said member.

17. Telegraphic apparatus controlled by received signals, including a member having motion in first and second directions, power driven means to move said member in first direction and operating for each received signal independently of the electrical character of the received signal, yielding means opposing motion of said member 45 in second direction, selectively operated means to oppose motion of said member in first direction to cause it to move in second direction against said yielding means, and a signal retransmitting contact operable by said member. 50

18. In a regenerative telegraphic repeater, a multiple cam, a signal controlled member, a series of contacts closable under control of said cam in variable sequence according to control by said signal controlled member, and invariable 60 means to open the closed contacts of said series in sequence.

19. In a telegraph repeater system for retransmitting signals each composed of a start impulse, 65 a rest impulse, and a plurality of variable code impulses, a start-stop cam, an armature controlled by received signals, a retransmitting contact, and means controlled by said cam and said armature jointly to operate said contact to transmit corresponding signals under the control of 70 said original signals, said armature exercising control for a small part only of each elementary impulse.

20. In a start-stop telegraph repeating system, start-stop means to transmit telegraph 75

signals each composed of a start impulse, a rest impulse, and a group of code impulses, a retransmitter, means to bring said retransmitter under control of said several impulses for a period in each impulse short in comparison with the duration of an impulse and substantially in the middle of each impulse and thereby retransmit a duplication of the original signal lagging substantially one-half of an impulse behind the received impulses, and locking means for said retransmitter effective between said periods.

21. In a telegraph system adapted for the transmission of signals each composed of an invariable start pulse and a plurality of variable code impulses, a cam member, a constantly rotating shaft, means to start said cam member by coupling said cam member to said shaft for each start impulse and maintain the coupling while the code impulses are being received, means controlled by the received signals to transmit a new set of signals corresponding electrically to the original signals, and means controlled by the cam member to time every individual impulse forming the signals.

22. In a telegraph system adapted for the transmission of signals each composed of an invariable start impulse and a plurality of variable code impulses, a constantly rotating shaft, a rotary member adapted to be coupled to said rotating shaft, a magnet operated by said signals, means controlled by the magnet to start said cam member by coupling said member to said shaft whenever a start impulse is received, cams carried by said member, a contact, and means controlled by the magnet to cause said cams to operate said contact to retransmit signals corresponding to the original signals.

23. Repeater mechanism for regenerating start-stop codes, which comprises, a transmitting cam started directly by a received starting impulse of a code, means associated with said cam for timing every impulse retransmitted including start and stop impulses, and means including a receiving magnet for determining the electrical nature of every retransmitted impulse.

24. In a telegraph repeater, a cam having an apex for each impulse of a start-stop code, means for starting said cam in response to a received starting impulse, and means controlled by received impulses and cooperating with each apex of said cam to transmit impulses corresponding to received impulses.

25. In a telegraph repeater, a cam having an apex for each impulse of a start-stop code, means for phasing said cam in response to a received timing impulse, and means controlled by received impulses and cooperating with each apex of said cam to transmit impulses corresponding to received impulses.

26. In a telegraphic repeating device, an electromagnet responsive to groups of signals, each

group consisting of synchronizing and selecting signals, means for controlling the beginning of the synchronizing and selecting signals of each group, mechanism controlled by the electromagnet in response to a synchronizing signal for rendering said means effective, a retransmitting contact, and means controlled by the electromagnet after said means has been rendered effective for determining the operation of the retransmitting contact to retransmit synchronizing and selecting signals.

27. In a regenerative telegraph repeater, a signal controlled member, a series of cam projections corresponding to impulses of spacing character, a second series of cam projections corresponding to impulses of marking character, a retransmitter, and means including a member engageable by all of said cam projections and engaging said retransmitter to control the retransmitter from one cam or the other according to the operation of the signal controlled member.

28. In a regenerative start-stop telegraph repeater, a signal controlled member, a series of parallel connected retransmitting contacts, one corresponding to the start and stop impulses, one corresponding to each of the code impulses, means to close and open the start-stop contact under control of the signal controlled member, means to close the code contacts under control of the signal controlled member, and means to open the code contacts independently of the signal controlled member.

29. In a start-stop regenerative repeater, a signal controlled member, a signal transmitting contact, a multiple lobed cam, means to initiate the operation of the multiple lobed cam under control of the signal controlled member, and means to operate the retransmitting contact under the joint control of the cam and the signal controlled member and effective to operate the retransmitting contact to retransmit a start impulse independent of the position of the signal controlled member and to operate the retransmitting contact to transmit code impulses whose timing severally is controlled by angular position of said multiple lobed cam and whose electrical characteristics severally are controlled by the position of the signal controlled member.

30. In a telegraphic repeating device, a contact member for retransmitting received signals, an element controlled by the received signals, a timing cam for determining an instant of beginning of retransmitted code signal impulses normally tending to rotate, means under control of said element for releasing said cam for rotation which cooperates during its rotation with said element for operating said contact member to control electrical characteristics in the retransmission of signals as determined by said element.

LOUIS M. POTTS.
